DESIGN FOR A COMBINED COMB AND BRUSH OR SIMILAR ARTICLE

Julius Kahn, Jersey City, N. J., assignor to E. I.
du Pont de Nemours & Company, Wilmington,
Del., a corporation of Delaware

Application September 14, 1939, Serial No. 87,219

Term of patent 3½ years

To all whom it may concern:

Be it known that I, Julius Kahn, a citizen of the United States and a resident of Jersey City, in the county of Hudson and State of New Jersey, have invented a certain new, original, and ornamental Design for a Combined Comb and Brush or Similar Article, of which the following is a specification, reference being had to the accompanying drawing, forming part thereof.

In the accompanying drawing:

Figure 1 is a bottom plan view of a combined comb and brush or similar article embodying my new design.

The characteristic features of the design for a combined comb and brush reside in the alternate rows of bristles and comb sections having the configuration and arrangement as shown.

I claim:

The ornamental design for a combined comb and brush or similar article, substantially as shown and described.

JULIUS KAHN.
